CONTROL MECHANISM

Clinton H. Dederick, Brentwood, Mo., assignor to
 The Emerson Electric Mfg. Company, St. Louis,
 Mo., a corporation of Missouri

Application June 21, 1943, Serial No. 491,583

14 Claims. (Cl. 172—239)

1

The present invention relates to a control mechanism. More particularly, it is directed to a control mechanism for accurately producing predetermined movement of a motor and some object displaced by the motor.

The invention is related to Serial No. 433,903, filed by the same inventor on April 21, 1943.

It is an object of this invention to provide a control that will produce precisely a predetermined amount of movement of the motor, and then stop. More particularly, it is an object to accomplish this through the use of selectable circuits in combination with slip ring mechanism that causes the circuits to be energized and stepping magnets energized a number of times determined by the number of rotations of the motor for operating the slip ring mechanism to neutral position.

A further object is to provide a mechanism of this kind which will cause the motor to start operating immediately upon commencement of the stepping operation and to continue operating until it has operated a number of times determined by the position of the control upon completion of the setting operation.

A further object of the invention is to provide a control of this type having a dial and pointer means cooperating with the dial to indicate both the desired setting of the mechanism driven by the motor and also at all times to indicate the actual position of that mechanism.

A further object of the invention is to provide a control of this type which will insure operation of the control to a full neutral position.

A further object is to provide a control of this type for use with a motor having limit switches preventing excess travel of the motor and adapted to open the circuits thereof upon such excess travel, stepping magnets in the control operated by breaker points opened and closed by the motor, with means to effect a restart of the motor in the other direction, if a limit switch open when the breaker points are closed.

In the drawings:

Fig. 1 is a wire diagram of the control;

Fig. 2 is a front view of the dial and knob;

Fig. 3 is a section through the dial and knob part of the control taken on the line 3—3 of Fig. 2;

Fig. 4 is a partial view of one of the stepping magnets and its relay switches;

Fig. 5 is a fragmental section of the switch taken on the line 5—5 of Fig. 4, and

Fig. 6 is a schematic view of a modification of the circuit.

2

Referring to Fig. 1, it may be seen that the control comprises a slip ring operator 10, power relays, stepping magnets and relays, a motor generally indicated at 11, and a breaker switch 12.

5 The motor construction is that disclosed in the copending application previously referred to. This motor may be used as a position means as, for instance, to position trimmer tabs on aircraft wings. The actuated mechanism has been symbolically here represented at M. Oscillation of the motor shaft will displace the member M up or down.

Diagrammatically, the slip ring mechanism comprises two substantially semi-circular outer segments 20 and 21. These segments are adapted to be wiped by a contact arm 22, electrically connected with an inside ring 23. A larger medium sized ring 24 is electrically connected at 25 with the segment 20. A smaller inside ring 26 is electrically connected at 27 with a segment 21.

15 A wiper 28 is constantly engaged with the inside ring 23, and is connected by a line 29 to a power line 29. The ring 24 is connected by a wiper 30 to a line 31. The ring 26 has a wiper 25 32 that is connected to a line 33.

20 It will be seen from the foregoing that power is always connected to the wiper arm 22. When the ring disc is moved in one direction or the other, it will cause the wiper arm to contact either the segment 20 or the segment 21. If the direction of rotation connects the wiper 22 with the segment 20, then the line 31 will be connected to power; whereas if the rotation is in the other direction, the line 33 will be connected to power.

25 30 The line 31 leads to a contact 35 which closes with a contact 36 on a switch 37 of a stepping magnet and relay 38 when the latter is deenergized. The contact 36 is in turn connected by a line 39 to one end of a coil 40 of a power relay 41. The other end of this coil is connected by a line 42 to a line 43, and through a manual switch 44 to ground.

35 35 The other line 33 is connected to a contact 45 which closes with a contact 46 on the relay switch 47 on another stepping magnet and relay 48, when that relay is deenergized. The contact 46 of the switch 47 is connected by a line 49 to one end of a coil 50 of another power relay 51. The other end of the coil 50 is connected by a line 52 to the line 43, and thence through the switch 44 to ground.

40 40 The power line 29 has an additional branch 29b. This branch ultimately leads through the shunt coil 55 of the motor 11, and thence to ground,

thus maintaining the field of the motor constantly energized to act as a dynamic brake, as will appear. The line 29b also branches at 29c, which ultimately leads to a normally open contact 56 on the switch 47. The line 29c likewise is connected with contacts 57 and 58 that are parts of the power relay 41, and contacts 59 and 60 that are parts of the relay 51. Also, a line 29d connects line 29b with a contact 61 on the switch 37, corresponding to the contact 56 on the switch 47.

The contact 56 on the switch 47 of the magnet 43 is adapted to close with a contact 63 that is connected by a line 64 with the line 39, when the magnet is energized. Similarly, the contact 61 of the switch 37 is adapted to close with a contact 65 that is connected by a line 66 with the line 43.

The contact 51 of the power relay 41 is adapted to close with a double contact 68 on that relay switch, when the relay is energized. The contact 68 is connected by a line 70 that leads to one of the limit switches of the motor. The contact 68 in its lower position is adapted to close with a contact 71 that is connected by line 72 to ground.

The contact 53, connected with the line 29c, is adapted to be closed with a contact 74 on the power relay 41, when it is energized. Contact 74 is connected by a line 75 into the coil 16 of the stepping magnet 43. The other end of this coil is connected by line 77 through the switch 12, to ground.

The contact 59, connected to the line 29c, is adapted to close with the contact 78 on the relay switch 51, when the relay is energized. The contact 78 is connected by a line 79 into the relay coil 80 of the magnet 33, the other end of which is connected with the line 77.

The contact 88 of the power relay 51 is adapted to close with the double contact 82 that is connected by a line 83 to the other limit switch on the motor. The contact 82 is likewise adapted to close with a contact 84 that is connected to the line 72 and thence to ground.

The motor 11 includes a rotor 90. One of the brushes of the rotor is connected by a line 91 with a movable contact 92 of the limit switch 93. The contact 92 normally closes with a contact 94 connected to the line 78. Upon excess travel of the motor in one direction the contact 92 is shifted to close with a contact 95 connected by a line 96 to ground.

The other brush in the motor is connected by a line 97 to a movable contact 98 of a limit switch 99. Normally the contact 98 is closed with a contact 100 connected to the line 83. Upon excess movement of the motor in the direction opposite that previously mentioned, the movable contact 98 will be shifted to close with a contact 101 connected, in turn, with the line 96 and ground.

Details of the motor and the limit switches and the switches 12, are set forth in the co-pending application referred to.

The stepping magnet construction is basically the same as that set forth in the co-pending application referred to, and consists of a toothed wheel attached to a shaft, with magnetic armature arms extending across the top edge of the wheel on opposite sides of a diameter thereof. When either magnet is energized it will draw its arm down against the wheel and move it in a corresponding direction the space of one notch or tooth on the wheel.

Figs. 2-5 show the details of the control mech-

anism necessary to understand the differences of the present application over the co-pending one. In Figs. 2 and 3 a mounting plate 110 has screw holes by means of which it may be attached to the instrument panel or other suitable support. The mounting plate 110 has a cylindrical flange 111 extending outwardly from the face thereof. This flange is provided with a dial 112. It provides a cup-shaped recess into which is mounted a cup-shaped pointer member 113, having an index as shown in Fig. 2, preferably formed by coloring one half of the disc black. The member 113 has an extending hub 114 bearing in a cylindrical opening through the mounting member 110 and rotatable therein. The hub 114 opposite the mounting member 111 supports a slip ring disc 115 which contains the two segments 20 and 21, and the slip rings 24 and 26. The brushes for these rings 24 and 26 are shown in contact with the rings as indicated. The hub 114 also supports a toothed wheel 116 that is engaged by a spring urged roller R to hold the member 113 and attached elements in position against fortuitous movement.

The outer portion of the cup-shaped member 113 is covered by a transparent plastic disc 117 to which is attached a knob 118. It will be seen that rotating the knob 118 turns the cup-shaped member 113 and with it the slip ring disc 115.

The hub 114 of the cup-shaped member 113 receives a main shaft 120 which extends rotatably through the hub 114 and has at its outer end an indicating disc 121 disposed beneath the transparent element 117. The indicating disc 121 provides a movable pointer 122 preferably emphasized by coloring one half of the disc black.

The shaft 120 likewise has secured thereto the contact or wiper arm 22 heretofore described. This wiper arm is caused to move when the shaft moves, by being secured to disc 123 having the slip ring 23 formed thereon, and engaged by the wiper 23.

The stepping magnet construction for moving the shaft 120 includes a toothed wheel 125, the same as that in the aforesaid co-pending application. This wheel is adapted to be engaged on its upper edge on opposite sides of the vertical by two stepping magnet arms, one of which is shown at 126 in Fig. 3, and the other of which is shown at 127 in Fig. 4.

The arms 126 and 127 are parts of armature constructions for the stepping relays 33 and 43. These two relays are of similar construction so that only one need be described. With the exception of the switch connections, these relays are identical in construction with those in the co-pending application.

The relay coil 76 is mounted on a bracket 130 secured to a wall 150 on the housing of the mechanism. The bracket 130 has an upstanding portion receiving an armature plate 131 pivoted thereon. A coil spring 132 is attached between a tail and the bracket 130 and an arm on the armature plate 131 to urge the plate upwardly and to maintain the arm 127, which is secured to the plate 131, away from the wheel 125.

The armature 131 actuates the switch 47.

A switch bar 133 overlies the arm 127 and is riveted to the arm 131, (Fig. 5) retaining the arm 127 therebetween. The bar 133 has the double contacts 46 and 56 thereon. When the coil 76 is not energized the spring 132 urges the armature 131 up, which brings the contact 46 against the fixed terminal 45, thereby establishing a circuit between them.

When the coil is energized the contact 56 is brought against the fixed contact 63. These actions occur coincidentally with the operation of the ratchet mechanism. Of course, this switch construction is merely typical as it is well known in the art how such mechanisms are constructed. It may be remarked that the contacts 46 and 56 are insulated from the switch bar 133.

In Fig. 1 there is shown a manual switch 44 for a purpose to be described. A modification, shown in Fig. 6, avoids the necessity of using this switch, and provides an automatic means to perform its functions.

In Fig. 6 a relay switch 140 is employed with its coil 141 in parallel with the rotor 90 of the motor 11. The coil controls a switch element 142 interposed in the line leading from the switch 12 to ground. The relay closes the switch 142 only when the rotor circuit is closed and the coil 141 energized. Otherwise the relay drops out, and breaks the circuits through the switch 12.

Operation

If this control and motor mechanism is to be used, for example, to set trimmer tabs on an airplane, it will be assumed that when the arm 22 is in the starting position shown in Fig. 1, and the dial in corresponding position as shown in Fig. 2, the tabs are in neutral position. In this starting position the arm 22 is between the segments 20 and 21, the field coil 55 is energized, and both ends of the rotor circuit are grounded, so that the motor windings can act as a brake on the motor.

By the present mechanism these tabs may be displaced upwardly or downwardly as desired. Assume that it is desired to set the trimmer tab upwardly to an angle of 10°. The operator will turn the knob 118, carrying with it the cup member 113 until the index thereon registers with the 10° "up" graduation, on the dial 112. This manual displacement of the member 113 does not change the position of the shaft 120 or the indicating disc 121 attached thereto. This movement is in the direction of the arrow shown in Fig. 1.

The attachment of the slip ring disc 115 to the hub of the cup member 113 causes the slip ring disc 115 to be moved to bring the segment 20 into contact with the contact wiper of the arm 22. Referring more particularly to Fig. 1, this will connect the power line 29a to the segment 20 and to the inner ring 24 from whence current flows through the line 31, to the contact 35 of the stepped magnet relay 38. Since the magnet at this time is not energized, the contact 36 is closed with contact 35 and the current, therefore, continues through the line 39 through the power relay coil 40, to line 42, to line 43, to manual switch 44, to ground. This causes the power relay 41 to lift, which causes the switch contacts 57 and 58 to close with the contacts 68 and 74 respectively, introducing power from the line 29c to these latter contacts. Power thus is introduced from the line 29c through contacts 57 and 68, line 70, limit switch contacts 94 and 92, line 91, rotor 90, line 97, limit switch contacts 98 and 100, line 83, contacts 82 and 84 and line 72 to ground. Current flowing through this circuit starts the rotor in one direction, as the field coil 55 is constantly in circuit. The motor shaft, through the reduction gearing G, operates the trimmer mechanism toward the selected position and starts rotation of the cam of switch 12.

At the same time as the foregoing motor cir-

cuit is closed, power flows from the line 29c through the contacts 58 and 74, to line 75, to stepping magnet relay coil 76, line 77, to the switch 12, and when the switch 12 is closed, the circuit will be completed through said switch to ground, energizing the coil 76.

The coil 76 breaks the contacts 46 and 45, which has no effect at this time. It also closes the contacts 53 and 63, which gives a power connection from the line 29c through the switch contacts and the line 64 to the line 39 thus shunting the slip ring switch 10 and the switch 37 whenever the coil 76 is energized to close the contacts 56 and 63.

At the same time as the switch 47 is operated, the arm 126 will be drawn down to strike the toothed wheel 125 and displace it the space of one tooth. This will cause the shaft 120 to be rotated a corresponding distance toward the previously made 10° selection, so that its indicating disc 121 registers one graduation to the right of zero on the dial 112.

It will be observed that the power relay coil 40 is held in circuit whenever the segment 20 is in contact with the arm 22 and the coil 80 of the stepping magnet 38 is not energized. The motor circuit is established through this circuit. It will be further observed, however, that the stepping magnet coil 76 is de-energized whenever the switch 12 breaks. Therefore, the coil 76 is given a number of impulses for any given number of rotations of the armature of the motor. Furthermore, each impulse steps the shaft 120 its pointer disc 121, and the slip ring disc 115, toward the pre-set position of the cup 113. The number of rotations of the motor and the number of steps of the pointer 121 are directly proportionate.

When the contact arm 22 is moved to the starting end of the segment 20, it will drop off of the end thereof. In order to complete the impulse despite breaking of the circuit through the slip ring, and to insure clearance of the arm 22 from the segment 20, the coil 76 will be maintained operative by the power relay 41 through the circuit closed by the contacts 56 and 63, which establish the aforementioned circuit that shunts the slip ring switches at the time the coil 76 is energized. This circuit holds until the motor opens switch 12, at which time the shunt circuit through contacts 56 and 63 is broken and both control and motor circuits are opened. By this shunt circuit a complete operation of the stepping magnet is assured, and the motor and control stop at the point where the arm 22 is disposed between the segments 20 and 21. The pointer will at such time coincide with the chosen graduation on the dial.

At this point the control is in neutral position but with both pointers registering 10° on the dial. The motor will have rotated a predetermined number of revolutions which are the number required to move the trimmer tab 10° upwardly. The circuits of the control will be opened, but the circuit from the line 29b through the field winding 55 of the motor will stay closed. The armature circuit will be grounded at both ends as at the start. Consequently, the winding 55 will act as a dynamic brake to stop the motor at once, and prevent any override of the trimmer tab.

From this 10° position the knob may be operated either upward or downward as desired. If turned upward it will reestablish the circuit previously mentioned until the tab and the control attain the advance positions selected. If turned

7

downwardly corresponding circuits on the other side of the control will be established, which are in every way symmetrical with the circuits described, and which send the current through the rotor in the other direction.

If the operator desires, he may change the setting of the control during the time it is stepping toward a previous setting. If this change is wholly above the point to which the control has already stepped, it will have no effect on the circuits other than to change the point at which they will ultimately open. If the change is sufficiently far in the opposite direction to that previously selected to cross over the position to which the control and the motor have advanced toward the earlier setting, then if the slip ring disc is moved so that it brings the break between the segments 20 and 21 to the arm 22 at the time the switch 12 is instantaneously open and the stepping magnet coil 80 released, the power relay 40 will immediately drop out. This will at once ground both sides of the armature motor and stop it. A quick passage of the slip ring disc to bring the opposite segment 21 under the arm 22 will energize the power relay 50 which is dependent only upon closing of the segment 21 with the arm 22 and release of the stepping magnet coil 76. This will close the other motor circuit through the contacts 60 and 82, and will close the other stepping magnet coil circuit through contacts 59 and 78 down to the switch 12. This switch will be closed as soon as the motor, operating in its new direction, can rotate the cam. The device will thereupon begin to step backward with the motor continuing to rotate in the other direction until the control reaches the new selected position.

It will be observed that this new position may be merely a reduction in the angularity of the trimmer tab in its previous direction, or it may be a reversal of the angularity of the trimmer tab, depending upon whether the knob is turned across the zero point on the dial or not. In other words, any stepping back of the control is the same in function whether the control starts from zero position and moves in a given direction, or starts from a previously advanced position and moves in the opposite direction.

If, in a reversal of the knob during a setting operation, the neutral position between the segments 20 and 21 is reached at the time the switch 12 is closed, to produce an impulse tending to advance the control in the direction from which it is being reversed, the holding circuit through the contacts 56 and 63 will keep the power relay coil 40 in circuit until the stepping operation is complete. The motor will be held in circuit because the power relay is held, until the completion of the stepping operation and breaking of the switch 12 to release coil 76. Hence the indicator 122 and the motor continue their corresponding movement in the original direction, and the indicator shows accurately the position of the motor.

However, if the swing-over from the segment 20 to the segment 21 is made so fast that the segment 21 is put in circuit before the cleanup operation of the stepping magnet 48, the circuit to the other power relay 50 cannot be made because it is dependent upon a release of the coil 76 to close the contacts 45 and 46. Therefore, the then operating motor circuit which passes through the contacts 82 and 84, and therefore is dependent upon deenergization of the coil 40, is not broken. Thus the motor, the shaft 120 with

its wiper arm 22, and indicating disc 121, will move together until the completion of the stepping operation, followed by release of the coil 76, and the indicator will always show the exact position of the trimmer tab at any time despite any change in the setting of the control in the middle of an operation. As soon as the cleanup operation is completed, and coil 76 is released, the switch 47 closes contacts 46 and 45, completing the circuit to the other power relay 50, and the backward operation can begin.

If the motor is caused to move an excessive distance in any direction, it will shift the limit switch in that direction as set forth in the co-pending application. Thus, if a setting of the control as heretofore, in a direction to bring segment 20 under the arm 22, is excessive, then after a predetermined number of revolutions of the motor the contact 92 of the limit switch 93 will move from the contact 94 to the contact 95. This will break the power input to the rotor and will connect both ends of the rotor circuit to ground. For example, this will pass from ground through the line 96, contacts 95 and 92, line 91, rotor 90, line 97, contacts 98 and 100, line 83, contacts 82 and 84, and line 12 to ground. This will produce the dynamic braking effect to stop the motor immediately.

If this braking occurs when the switch 12 is closed, the power relay 40 will stay energized, holding the stepping magnet 48 up, through the contacts 56 and 63, thus preventing release of these circuits even when the segment 20 is moved from the arm 22, and the segment 22 is put thereunder. The circuit to the other power relay 50 cannot close, because of separation of the contacts 45 and 46, so that the mechanism remains locked. To release it, the operator opens manual switch 44, which releases the power coil 40 and the stepping coil 76, breaking the holding circuits thereof. Upon subsequent reclosing of the switch 44, the power coil 50 will be energized and the other side of the control operated to step the device back.

45 It will be understood that the other limit switch 99 functions in like manner.

When the auxiliary relay 140 of Fig. 6 is used, the release above is effected automatically. In this case the closure of the stepping magnet circuit is dependent upon energization of one of the motor circuits, as the coil 141 is in parallel with the rotor. Hence, if the operation of a limit switch opens a rotor circuit, the stepping magnet circuit opens, and upon resetting of the control onto the other segment, the opposite rotor circuit is closed. When magnet 140 is deenergized due to both ends of coil being connected to ground, the switch 142 is opened, which breaks the circuit to the stepping relay coil. Switch 47 then closes points 46 and 45 completing the circuit to power relay coil 50 when the control is turned for opposite rotation.

For example, if the motor circuit opens by the limit switch 93 grounding at 95, then the coil 65 76 of the stepping magnet 48 is deenergized by the opening of the switch 142, thus releasing the holding circuit for the power relay 40. At this time both ends of the rotor are grounded. Thereafter, when the segment 21 is displaced 70 under the arm 22, the power relay 50 is put in circuit, which lifts the contact 82 from the grounded contact 84 to the hot contact 60. This then establishes a reversing rotor circuit that grounds through line 96. And of course the 75 establishment of the new rotor circuit reener-

gizes the auxiliary relay 140, so that the control will step back in proportion to the number of revolutions of the motor, or more exactly, the number of operations of the switch 12. As soon as the rotor reverses sufficiently to permit the snap limit switch 93 to return the contact 92 to the contact 94, the grounding of the new rotor circuit is effected through the now grounded contact 68 of the other power relay.

What is claimed is:

1. In a mechanism of the kind described, a motor and a control for causing a predetermined number of revolutions of the motor, said control including a pre-set device and a follower device, said devices being adapted to be in a neutral relative position, the pre-set device being adapted to be operated to establish circuits and the follower device being adapted to be moved from neutral position to a position to break said circuits, a first circuit through the pre-set device in operated position to operate the motor, a second circuit controlled by the pre-set device, operating means for the follower device to displace the same toward position to break the circuits a predetermined degree upon each energization thereof, a motor switch means made and broken in a cycle a predetermined number of times for each revolution of the motor, said second circuit including the operating means and the motor switch means whereby upon operation of the pre-set device the motor will start, and the follower device will be moved toward circuit breaking condition, and will break the circuits after a predetermined number of revolutions of the motor, said operating means for the follower device including a switch closed upon operation thereof, and a shunt circuit through said switch to maintain the first and second circuits closed regardless of the pre-set device as long as said operating means is operated.

2. In a mechanism of the kind described, a motor and a control for causing a predetermined number of revolutions of the motor, said control including a pre-set device and a follower device, said devices being adapted to be in a neutral relative position, the pre-set device being adapted to be operated to establish circuits and the follower device being adapted to be moved from neutral position to a position to break said circuits, a first circuit, said first circuit including a single relay and switches automatically controlled thereby, one of said switches being adapted to close a motor circuit whereby the motor may operate when the relay is energized, a second circuit including another of said relay switches which is closed when the relay is energized, operating means for the follower device to displace the same toward position to break the circuits a predetermined degree upon each energization thereof, a motor switch means made and broken in a cycle a predetermined number of times for each revolution of the motor, said second circuit including the operating means and the motor switch means, whereby upon operation of the pre-set device the motor will start, and the follower device will be moved toward circuit breaking condition, and will break the circuits after a predetermined number of revolutions of the motor.

3. In a mechanism of the kind described, a motor and a control for causing a predetermined number of revolutions of the motor, said control including a pre-set device and a follower device, said devices being adapted to be in a neutral relative position, the pre-set device being adapted to

be operated to establish circuits and the follower device being adapted to be moved from neutral position to a position to break said circuits, a first circuit, said first circuit including a relay and switches operated thereby, one of said switches being adapted to close a motor circuit whereby the motor may operate, a second circuit including another of said relay switches, operating means for the follower device to displace the same toward position to break the circuits a predetermined degree upon each energization thereof, a motor switch means made and broken in a cycle a predetermined number of times for each revolution of the motor, said second circuit including the operating means and the motor switch means, whereby upon operation of the pre-set device the motor will start, and the follower will be moved toward circuit breaking condition, and will break the circuits after a predetermined number of revolutions of the motor, said pre-set device and follower device comprising a wiper means and slip ring means, adapted to be disengaged in neutral position, one of which means is displaceable from neutral position a selectable distance and in such displacement brought into contact with the other, and the other being adapted to be displaced in contact with the one until it reaches the neutral position thereon.

4. In a mechanism of the kind described, a reversible motor, circuit therefor, and a control for causing a predetermined number of revolutions of the motor in either direction, said control including a pre-set device and a follower device, said devices being adapted to be in neutral relative position, the pre-set device being adapted to be operated to establish a forward set of circuits and a reverse set of circuits, and the follower device being adapted to be moved upon establishment of one of said circuits a distance from neutral position sufficient to break the circuit and reestablish neutral conditions, the setting of the pre-set device in either direction determining the distance of movement of the follower device in that direction required to break the circuits, a forward first circuit through the pre-set device set in one direction to cause operation of the motor in a forward direction, a reverse first circuit through the pre-set device set in the other direction to cause operation of the motor in the other direction, each of said circuits including a relay automatically energized by the setting of the pre-set device to close the proper motor circuit, forward operating means to operate the follower device to displace the same in forward direction toward position to break the circuits, reverse operating means to operate the follower device to displace the same in reverse direction toward position to break the circuits, a motor switch means made and broken in a cycle a predetermined number of times per revolution of the motor, a second forward circuit controlled by the relay of the first forward circuit and including the forward operating means and the motor switch, and a second reverse circuit controlled by the relay of the reverse first circuit and including the reverse operating means and the motor switch, whereby upon operation of the pre-set device in either direction the motor will start in a corresponding direction, and the follower device will be successively moved toward circuit breaking condition a predetermined degree per each revolution of the motor.

5. In a mechanism of the kind described, a reversible motor and a control for causing a

predetermined number of revolutions of the motor in either direction, said control including a pre-set device and a follower, said devices being adapted to be in neutral relative position, the pre-set device being adapted to be operated to establish a forward set of circuits and a reverse set of circuits, and the follower device being adapted to be moved upon establishment of one of said circuits a distance from neutral position sufficient to break the circuit and reestablish neutral conditions, the setting of the pre-set device in either direction determining the distance of movement of the follower device in that direction required to break the circuits, a forward first circuit through the pre-set device set in one direction to cause operation of the motor in a forward direction, a reverse first circuit through the pre-set device set in the other direction to cause operation of the motor in the other direction, forward operating means to operate the follower device to displace the same in forward direction toward position to break the circuits, reverse operating means to operate the follower device to displace the same in reverse direction toward position to break the circuits, a motor switch means made and broken in a cycle a predetermined number of times per revolution of the motor, a second forward circuit controlled by the first forward circuit and including the forward operating means and the motor switch, and a second reverse circuit controlled by the reverse first circuit and including the reverse operating means and the motor switch, whereby upon operation of the pre-set device in either direction the motor will start in a corresponding direction, and the follower will be successively moved toward circuit breaking condition a predetermined degree for each revolution of the motor, and means on each operating means adapted to close the other first circuit only when said operating means is inoperative.

operating means and the motor switch, whereby upon operation of the pre-set device in either direction the motor will start in a corresponding direction, and the follower will be successively moved toward circuit breaking condition a pre-determined degree for each revolution of the motor, and means to prevent closure of one first circuit when the other operating means is in operated position, said means having an element movable with said operating means.

10 movable with said operating means.

7. In a mechanism of the kind described, a reversible motor and a control for causing a pre-determined number of revolutions of the motor in either direction, said control including a pre-set device and a follower, said devices being adapted to be in neutral relative position, the pre-set device being adapted to be operated to establish a forward set of circuits and a reverse set of circuits, and the follower device being adapted to be moved upon establishment of one of said circuits a distance from neutral position sufficient to break the circuit and reestablish neutral conditions, the setting of the pre-set device in either direction determining the distance of movement of the follower device in that direction required to break the circuits, a forward first circuit through the pre-set device set in one direction to cause operation of the motor in a forward direction, a reverse first circuit through the pre-set device set in the other direction to cause operation of the motor in the other direction, forward operating means to operate the follower device to displace the same in forward direction toward position to break the circuits, reverse operating means to operate the follower device to displace the same in reverse direction toward position to break the circuits, a motor switch means made and broken in a cycle a predetermined number of times per revolution of the motor, a second forward circuit controlled by the first forward circuit and including the forward operating means and the motor switch, and a second reverse circuit controlled by the reverse first circuit and including the reverse operating means and the motor switch, whereby upon operation of the pre-set device in either direction the motor will start in a corresponding direction, and the follower will be successively moved toward circuit breaking condition a predetermined degree for each revolution of the motor, and means comprising control means on each operating means to shunt the pre-set device in the corresponding first circuit when the corresponding operating means is in operated position.

8. In a mechanism of the kind described, a reversible motor and a control for causing a pre-determined number of revolutions of the motor in either direction, said control including a pre-set device and a follower, said devices being adapted to be in neutral relative position, the pre-set device being adapted to be operated to establish a forward set of circuits and a reverse set of circuits, and the follower device being adapted to be moved upon establishment of one of said circuits a distance from neutral position sufficient to break the circuit and reestablish neutral conditions, the setting of the pre-set device in either direction determining the distance of movement of the follower device in that direction required to break the circuits, a forward first circuit through the pre-set device set in one direction to cause operation of the motor in a forward direction, a reverse first circuit through the pre-set device set in the other direction to cause operation of the motor in the other direction

tion, forward operating means to operate the follower device to displace the same in forward direction toward position to break the circuits, reverse operating means to operate the follower device to displace the same in reverse direction toward position to break the circuits, a motor switch means made and broken in a cycle a predetermined number of times per revolution of the motor, a second forward circuit controlled by the first forward circuit and including the forward operating means and the motor switch, and a second reverse circuit controlled by the reverse first circuit and including the reverse operating means and the motor switch, whereby upon operation of the pre-set device in either direction the motor will start in a corresponding direction, and the follower will be successively moved toward circuit breaking condition a predetermined degree for each revolution of the motor, means on each operating means to shunt the pre-set device in the corresponding first circuit when the corresponding operating means is in operated position, and means to prevent closure of one first circuit when the other operating means is in operated position.

9. In a mechanism of the kind described, a reversible motor and a control for causing a predetermined number of revolutions of the motor in either direction, said control including a pre-set device and a follower, said devices being adapted to be in neutral relative position, the pre-set device being adapted to be operated to establish a forward set of circuits and a reverse set of circuits, and the follower device being adapted to be moved upon establishment of one of said circuits a distance from neutral position sufficient to break the circuit and reestablish neutral conditions, the setting of the pre-set device in either direction determining the distance of movement of the follower device in that direction required to break the circuits, a forward first circuit through the pre-set device set in one direction to cause operation of the motor in a forward direction, a reverse first circuit through the pre-set device set in the other direction to cause operation of the motor in the other direction, forward operating means to operate the follower device to displace the same in forward direction toward position to break the circuits, reverse operating means to operate the follower device to displace the same in reverse direction toward position to break the circuits, a motor switch means made and broken in a cycle a predetermined number of times per revolution of the motor, a second forward circuit controlled by the first forward circuit and including the forward operating means and the motor switch, and a second reverse circuit controlled by the reverse first circuit and including the reverse operating means and the motor switch, whereby upon operation of the pre-set device in either direction the motor will start in a corresponding direction, and the follower will be successively moved toward circuit breaking condition a predetermined degree for each revolution of the motor, means on each operating means to shunt the pre-set device in the corresponding first circuit when the corresponding operating means is in operated position, and means to prevent closure of one first circuit when the other operating means is in operated position, and means to release the operated means from operated position when the motor circuit is opened.

10. In a mechanism of the kind described, a reversible motor and a control for causing a pre-

determined number of revolutions of the motor in either direction, said control including a pre-set device and a follower, said devices being adapted to be in neutral relative position, the pre-set device being adapted to be operated to establish a forward set of circuits and reverse set of circuits, and the follower device being adapted to be moved upon establishment of one of said circuits a distance from neutral position sufficient to break the circuit and reestablish neutral conditions, the setting of the pre-set device in either direction determining the distance of movement of the follower device in that direction required to break the circuits, a forward first circuit through the pre-set device set in one direction to cause operation of the motor in a forward direction, a reverse first circuit through the pre-set device set in the other direction to cause operation of the motor in the other direction, forward operating means to operate the follower device to displace the same in forward direction toward position to break the circuits, reverse operating means to operate the follower device to displace the same in reverse direction toward position to break the circuits, a motor switch means made and broken in a cycle a predetermined number of times per revolution of the motor, a second forward circuit controlled by the first forward circuit and including the forward operating means and the motor switch, and a second reverse circuit controlled by the reverse first circuit and including the reverse operating means and the motor switch, whereby upon operation of the pre-set device in either direction the motor will start in a corresponding direction, and the follower will be successively moved toward circuit breaking condition a predetermined degree for each revolution of the motor, means on each operating means to shunt the pre-set device in the corresponding first circuit when the corresponding operating means is in operated position, and means to prevent closure of one first circuit when the other operating means is in operated position, and means to release the operated means from operated position when the motor circuit is opened, comprising a relay coil in the motor circuit and a switch operated thereby in series with the motor switch.

11. In a mechanism of the kind described, a motor, a preselector device displaceable from a neutral position selectable distances, a circuit established through said preselector device only when it is out of neutral position, a power relay coil in said circuit, a relay switch means operated by said coil, a second circuit through said relay switch means to the motor, a control operating relay, a switch cycled a predetermined number of times for each revolution of the motor, a third circuit including the relay switch when the relay is operated, the control operating coil and the motor switch, said third circuit being adapted to be made and broken during each cycle of the motor switch, a switch closed by the control relay, and a shunt circuit for the power relay closed by said last named switch, said shunt circuit shunting the preselector means from the power relay circuit, and means operated by said control relay and movable with respect to the preselector means toward neutral position a predetermined distance for each operation of said relay.

12. In a mechanism of the kind described, a reversible motor, a shaft rotated thereby, a switch cycled from the shaft a predetermined number of times per revolution of the shaft, a pair of limit switches, the first operated after a certain

number of revolutions of the motor in one direction and the other operated after a certain number of revolutions of the motor in the other direction, a control device including a selectively displaceable device and a follower, the follower being adapted to assume a neutral position relative to the displaceable device and adapted to be moved in either direction relative to said device, circuit making means including the device and the follower when not in neutral position, a forward and a reverse power relay, a forward and a reverse second stepping relay, each relay including switch means operated from a first to a second position upon energization of the said relays, a forward first circuit through the circuit making means, the second stepping relay switch in first position, the first power relay coil, to ground, a forward second circuit established upon energization of the first power relay through its switch in second position through a forward limit switch through the motor in one direction, through the reverse limit switch, through the second power relay switch in first position, to ground, a third forward circuit through the first power relay switch in second position, through the first stepping relay coil, and through the motor switch to ground, whereby the first stepping relay is operated to second position, a shunt circuit through the first stepping relay in second position, the first power relay coil to ground, and means operated by the stepping relay coil to move the follower toward neutral position a predetermined distance for each energization of said relay coil, the forward limit switch being adapted to connect its end of the motor circuit to ground, means to break the third circuit, to release the operating means, and symmetrical reverse circuits corresponding to said forward circuits.

13. In a mechanism of the kind described, a reversible motor, a shaft rotated thereby, a switch cycled from the shaft a predetermined number of times per revolution of the shaft, a pair of limit switches, the first operated after a certain number of revolutions of the motor in one direction and the other operated after a certain number of revolutions of the motor in the other direction, a control device including a selectively displaceable device and a follower, the follower being adapted to assume a neutral position relative to the displaceable device and adapted to be moved in either direction relative to said device, a circuit making means including the device and the follower when not in neutral position, a forward and a reverse power relay, a forward and a reverse second stepping relay, each relay including switch means operated from a first to a second position upon energization of the said relays, a forward first circuit through the circuit making means, the second stepping relay switch in first position, the first power relay coil, to ground, a forward second circuit established upon energization of the first power relay through its switch in second position through a forward limit switch through the motor in one direction, through the reverse limit switch, through the second power relay switch in first position, to ground, a third forward circuit through the first power relay switch in second position, through the first stepping relay coil, and through the motor switch to ground, whereby the first stepping relay is operated to second position, a shunt circuit through the first stepping relay in second position, the first power relay coil to ground, and means operated by the stepping relay coil to move the follower toward neutral position a predetermined distance for each energization of said relay coil, the forward limit switch being adapted to connect its end of the motor circuit to ground, means to break the third circuit, to release the operating means, and symmetrical reverse circuits corresponding to said forward circuits.

relay switch in first position, to ground, a third forward circuit through the first power relay switch in second position, through the first stepping relay coil, and through the motor switch to ground, whereby the first stepping relay is operated to second position, a shunt circuit through the first stepping relay in second position, the first power relay coil to ground, and means operated by the stepping relay coil to move the follower toward neutral position a predetermined distance for each energization of said relay coil, the forward limit switch being adapted to connect its end of the motor circuit to ground, means to break the third circuit, to release the operating means, and symmetrical reverse circuits corresponding to said forward circuits.

14. In a mechanism of the kind described, a reversible motor, a shaft rotated thereby, a switch cycled from the shaft a predetermined number of times per revolution of the shaft, a pair of limit switches, the first operated after a certain number of revolutions of the motor in one direction and the other operated after a certain number of revolutions of the motor in the other direction, a control device including a selectively displaceable device and a follower, the follower being adapted to assume a neutral position relative to the displaceable device and adapted to be moved in either direction relative to said device, a circuit making means including the device and the follower when not in neutral position, a forward and a reverse power relay, and forward and a reverse second stepping relay, each relay including switch means operated from a first to a second position upon energization of the said relays, a forward first circuit through the circuit making means, the second stepping relay switch in first position, the first power relay coil, to ground, a forward second circuit established upon energization of the first power relay through its switch in second position through a forward limit switch through the motor in one direction, through the reverse limit switch, through the second power relay switch in first position, to ground, a third forward circuit through the first power relay switch in second position, through the first stepping relay coil, and through the motor switch to ground, whereby the first stepping relay is operated to second position, a shunt circuit through the first stepping relay in second position, the first power relay coil to ground, and means operated by the stepping relay coil to move the follower toward neutral position a predetermined distance for each energization of said relay coil, the forward limit switch being adapted to connect its end of the motor circuit to ground, means to break the third circuit, to release the operating means, and symmetrical reverse circuits corresponding to said forward circuits, said breaking means comprising a relay coil in the motor circuit and a switch operated thereby in series with the motor switch.

CLINTON H. DEDERICK.
